METHOD AND APPARATUS FOR INSTALLING INSERTS IN PLASTIC BODIES

Original Filed July 2, 1919

Patented Sept. 16, 1924.

1,508,545

UNITED STATES PATENT OFFICE.

HARRY C. FOSTER, OF DAYTON, OHIO.

METHOD AND APPARATUS FOR INSTALLING INSERTS IN PLASTIC BODIES.

Application filed July 2, 1919, Serial No. 308,116. Renewed August 7, 1924.

To all whom it may concern:

Be it known that I, HARRY C. FOSTER, a citizen of the United States, residing at Dayton, in the county of Montgomery and State of Ohio, have invented certain new and useful Improvements in Methods and Apparatus for Installing Inserts in Plastic Bodies, of which the following is a specification.

10 This invention relates to concrete structures and more particularly to an apparatus for installing expansion joints or inlays in concrete bodies and especially an inlaid felt strip in concrete roadways designed to compensate for the expansion and contraction of the successive sections of concrete.

The object of the invention is to simplify the apparatus, as well as the means and mode of operation of installing felt strips or other inlays in bodies of plastic or semi-fluid materials, whether the same be concrete or other like material, whereby such inserts may be easily and quickly adjusted in desired position and securely held during their investment in the plastic or semi-fluid materials and whereby the efficiency of such inserts is materially increased, as well as the rapidity with which such inserts or joints may be made.

20 30 A further object of the invention is to provide means for securely bracing or holding the insert against lateral displacement and also to prevent it being floated upward or elevated by the semi-fluid mixture poured about the insert.

40 A further object of the invention is to provide supporting means for the insert which may be easily and quickly detached and removed without disturbing the position of the insert in the plastic or semi-fluid body.

With the above primary and other incidental objects in view as will more fully appear in the specification, the invention consists of the features of construction, the parts and combinations thereof and the mode of operation or their equivalents as herein-after described and set forth in the claims.

50 Referring to the drawings Fig. 1 is a perspective view of the installing apparatus forming the subject matter hereof positioned across the roadway or concrete form with a portion of an insert engaged therewith. Fig. 2 is a transverse sectional view of the supporting member and insert shown in Fig. 1. Fig. 3 is a detail sectional view of

portions of two adjacent concrete bodies with the inserted member therebetween. Figs. 4 and 5 are detail views of modifications of the insert engaging means. Fig. 6 60 is a bottom plan view of a modified arrangement of the supporting fingers and attachment skewers.

Like parts are indicated by similar characters of reference throughout the several 65 views.

While the invention is herein shown and described for illustrative purposes as applied to the insertion of flexible or yielding expansion joint members in concrete roadways, 70 it is to be understood that the invention is not limited to this application but may be employed for analogous purposes in structures other than concrete roadways. Although the invention is thus capable of general use it finds its principal application at the present time in concrete road building. It is the custom and practice in concrete road construction to separate the road bed into independent successive sections or blocks 80 of approximately fifty feet in length, but which may be more or less, such sections being separated one from another by an intervening strip of some yielding material which will compensate for the relative ex- 85 pansion and contraction of the blocks or sections at varying temperature. The usual insert is a strip of felt impregnated with asphaltum but other comparatively soft or yielding bodies may be employed. Much 90 difficulty has been experienced in effecting the insertion of these compensating bodies or strips, the usual method being to provide a supporting board parallel with the strip, 95 against which the strip is held temporarily by stakes driven into the ground. During the pouring of the concrete the mixture frequently flows between the insert strip and the supporting board, thus forcing the strip out of alignment and making a crooked 100 joint. After the concrete has been poured and before it has set, the supporting board is withdrawn, the intent being to leave the felt strip embedded in the plastic or semi-fluid body. However, in practice, the withdrawal of the board frequently disturbs the 105 inserted strip causing it to be tilted or inclined to the vertical whereby the abutting faces of the successive sections will be bevelled or tapered instead of vertical. Under such conditions the subsequent expansion of the adjacent sections under influence of sum-

mer heat causes one section to crawl or climb the tapered or bevelled face of the opposing section and thus be elevated above the plane thereof, causing an offset or uneven joint. Another difficulty experienced in the use of a board as a support is the fact, that the strip tends to pull out of the mixture with the board and is assisted in this movement by the flow of the concrete mixture as the board is lifted, which tends to float the flexible insert strip out of its adjusted position, allowing the successive sections to be joined integrally one with the other beneath the lower edge of the insert and causing the insert to be projected above the top plane of the roadway. The present invention is designed to overcome these difficulties by holding the inserted strip stationary in its adjusted position and enabling the disengagement of the supporting means without disturbance of the strip or the adjacent bodies of plastic or semi-fluid material.

In the drawing 1 represents the bottom of the road bed or the earth surface and 2—2 the form boards located at opposite longitudinal margins of the roadway. Resting upon the form boards 2 is a transverse supporting bar 3 the lower face of which is somewhat arched to agree with the crown of the roadway, while the opposite ends of the supporting bar 3 are provided with projecting ears 4 perforated to receive attachment stakes 5. The stakes 5 are driven through the ears 4 into the earth at opposite sides of the roadway or form and serve to hold the supporting bar 3 immovable in its transverse relation with the form. Projecting from the under face of the supporting bar 3 is a plurality of dependent fingers or pins 6 arranged in pairs. The fingers or pins of each pair are separated one from the other a distance substantially equal to the thickness of the inserted strip or expansion joint. These pairs of supporting fingers 6 are arranged at spaced intervals in aligned relation, the succeeding pairs being separated distances in accordance with the flexibility of the insert strip to be operated upon. The fingers 6, may if desired be slightly tapered as shown in Fig. 4, to facilitate subsequent withdrawal from the body of plastic or semi-fluid material. The insert strip 7, whether the same be felt impregnated with asphaltum or any other separating or parting material, is positioned between the fingers or pins 6 extending in parallel relation with the supporting bar 3 from one form board 2 to the other and is held by the fingers or pins 6 in aligned and vertical position. The strip 7 is secured in this position to its support by transverse pins or skewers 8 which are projected through eyes 9, in the fingers or pins 6 and through the insert strip 7 intermediate said pins, as shown at the right in Fig. 1 and also in Figs. 2, 4 and 5. This skewer may be a simple pin, as shown in Figs. 4 and 5, or it may be shaped as shown in Figs. 1 and 2, whereby it will retain its permanent relation with the support. In these figures the skewer 8 is bent to substantially U shape one leg of which is sharpened and extended through the eyes 9 of the fingers 6, while the other leg extends through a transverse opening in the supporting bar 3. This transverse opening is preferably reinforced by a short section of pipe or tubing 10 and is counterbored or enlarged at 11 to accommodate a head 12 carried by the end of the skewer leg extending through such opening. The U shaped skewer is thus capable of a reciprocatory movement to and fro through the eyes 9 and the bushing 11, the withdrawal of the skewer being limited by the engagement of the head 12 with the end of the counterbore 11. In its withdrawn position the pointed leg of the skewer clears the intermediate space between the supporting fingers 6 to permit the insertion of the strip 7. Upon the return of the skewer the pointed extremity penetrates the strip interposed between the fingers 6 and holds it in fixed relation with the support. There may be any number of these attachment devices provided although only three have been shown in Fig. 1. Not only is the strip 7 held against vertical displacement by the skewers 8 but by the same means is held tensioned to prevent lateral bulging under the influence of the pressure of the plastic material being poured upon one side or the other of the insert.

The insert strip being supported, as shown in Fig. 1, in vertical position and extending across the form, the concrete or other plastic or semi-fluid material is poured upon both sides of the insert. While the distribution of material is substantially equal on both sides, the support of the strip is such that a preponderance of material or pressure upon one side or the other will not materially affect the disposition of the insert strip. The concrete material is "struck off" in the usual manner to form the uniform top surface of the concrete section. Before the material has become hardened or set, the skewers 8 which are partially embedded in the plastic material and partially extended above the level thereof, are withdrawn to disengage them from the insert strip 7. The plastic or semi-fluid condition of the material readily permits this withdrawal of the skewers 8. The stakes 5 are then removed and the supporting bar 3 lifted vertically, withdrawing the supporting fingers 6 from the opposite sides of the strip 7 leaving the strip embedded in the material. The pressure of the semi-fluid or plastic material upon the strip 7 intermediate the pins 6 is sufficient to hold the strip against displace-

ment while the pins are being withdrawn and the concrete material is sufficiently plastic or semi-fluid to readily close the small openings from which the fingers 6 are withdrawn. If so desired the stakes 5 may be left in position to serve as guides to insure the withdrawal of the supporting bar 3 and the fingers 6 in a perfectly aligned relation with the inserted strip 7.

10 By this means the concrete material flows directly into contact with the strip during the pouring operation thus obviating any possibility of air pockets being formed and the strip is held in alignment and against any 15 shifting movement under the influence or pressure of the concrete material until the form is completely filled and "struck off," after which the support is readily detached.

In lieu of the U shaped skewers 8, a simple 20 pin 13 may be employed. This pin is inserted through the eyes 9 and interposed strips 7 in the manner before described. The pin 13 is formed with an eye or head 14 to which is attached a chain or cable 15, the opposite end of which is secured to the support 3 above the finished level of the concrete. After the pouring of the concrete has been completed the skewer pin 13 may be disengaged from the strip 7 and fingers 6, by pulling upon the chain or cable 15 to withdraw 30 the skewer 13. This operation is readily permitted by the "unset" or semi-plastic condition of the concrete at this stage of operation.

35 In Fig. 5 there is shown a further modification in which a skewer pin 16, similar to the pin 13, is inserted through eyes in the fingers 6 in an inclined or diagonal relation, whereby the upper end of the skewer pin 0 projects above the finished level of the concrete. This retaining device may be withdrawn by grasping the protruding end thereof and withdrawing it from its engagement with the finger 6 and interposed strip 7. In 5 this Fig. 5, one of the supporting fingers 6 is shown of greater length than the other. Forming one finger shorter than the other enables the adaption of the device to certain 0 types of inserts having lateral projections or interlocking anchorage flanges as shown in Fig. 5.

In Fig. 6 there is shown a modified arrangement of the fingers 6 and skewers 8 which in practice under the present conditions has been found to be the preferred form. In this form the fingers 6 forming each pair are offset longitudinally in relation with the bar 3, thus arranging the fingers in alternating or staggered relation. This 0 enables the plastic material to bear directly opposite each finger and there is less tendency for the strip to be displaced in withdrawing the device. The construction affords greater engagement with the plastic 5 body and less frictional engagement with

the support. It is not at all essential that the skewers be passed through eyes in the fingers. As shown in Fig. 6 these may pierce the strip at one side of the finger. Being connected directly with the bar 3 by the 70 opposite leg of the U shaped member the skewers 8 prevent any shifting of the strip either upwardly or downwardly equally as well as when extended through the fingers.

75 By this means the concrete material flows directly into contact with the strip during the pouring operation thus obviating any possibility of air pockets being formed and the strip is held in alignment and against any 80 shifting movement under the influence or pressure of the concrete material until the form is completely filled and "struck off," after which the support is readily detached.

In lieu of the U shaped skewers 8, a simple 85 pin 13 may be employed. This pin is inserted through the eyes 9 and interposed strips 7 in the manner before described. The pin 13 is formed with an eye or head 14 to which is attached a chain or cable 15, the opposite end of which is secured to the support 3 above the finished level of the concrete. After the pouring of the concrete has been completed the skewer pin 13 may be disengaged from the strip 7 and fingers 6, by pulling upon the chain or cable 15 to withdraw 90 the skewer 13. This operation is readily permitted by the "unset" or semi-plastic condition of the concrete at this stage of operation.

95 While in order to comply with the statute the invention has been herein described in language more or less specific as to certain structural features, it is to be understood that the invention is not limited to the specific details shown, but that the means and construction herein disclosed comprises but one of several modes of putting the invention 100 into effect and the invention is therefore claimed in any of its forms or modifications within the legitimate and valid scope of the appended claims.

Having thus described my invention I 105 claim:

1. In a device of the character described, a supporting beam to be arranged transversely in elevated relation above the finished surface of a roadway, a plurality of pins projecting downward from the underside of said beam in fixed relation with each other and arranged in two parallel series between which an insert strip may be positioned, means for supporting the beam in elevated relation above the finished surface of the 110 roadway.

2. In a device of the character described, a transverse supporting member to be arranged in elevated position above the roadway, a plurality of rigid, relatively fixed pins projecting downward from the under face of the supporting member and arranged in staggered relation for engaging at spaced intervals the opposite sides of an interposed insert strip, the strip being exposed to the deposit of road making material, intermediate such pins, throughout substantially its full height.

3. In a device of the character described, the combination with an insert strip to be 125

- embedded in a body of plastic material, of a supporting bar to be arranged in transverse relation above a body of plastic material, and a series of substantially straight, dependent pins immovably mounted on said bar in spaced relation one with another and adapted to extend on opposite sides of said insert strip between which the full height of said strip is exposed, means for supporting the bar independent of the pins, the pins being capable of withdrawal from the body of plastic material independent of the insert strip with minimum disturbance of the material.
- 15 4. The combination with an insert strip to be embedded in a body of plastic material of a supporting bar, a plurality of fingers carried thereby and arranged in pairs between which fingers comprising the pairs of fingers the strip is supported, and transverse skewers extending through the strip and detachably engaged with the fingers.
- 20 5. In a device of the character described, a supporting bar to be arranged transversely in relation with a roadway, insert strip supporting means carried by the supporting bar and extending on opposite sides of the insert strip for supporting the strip during the deposit of plastic material thereabout, said supporting means being withdrawable from the deposit of plastic material independent of the strip and means for guiding the supporting means during such withdrawal movement through a predetermined path of movement in relation with the strip whereby the position of the strip in the deposit of plastic material will be undisturbed.
- 25 6. Means for installing an insert strip in a body of plastic material comprising a supporting bar positioned transversely across the mold or form above the level of the body of plastic material, having parallel supporting fingers between which the strip is to be inserted, said fingers being provided with transverse eyes, and an attachment member extending through the said eyes and intervening strip.
- 30 7. Means for installing an insert strip in a body of plastic material comprising a supporting bar, parallel fingers carried by the bar and straddling the insert strip, said fingers having transverse openings therein, and a substantially U-shaped skewer, one leg of which is slidably mounted in the supporting bar, the other leg of which extends through the transverse openings in said fingers and through the strip when inserted therebetween.
- 35 8. Means for installing an insert strip in a body of plastic material comprising a supporting bar, parallel fingers carried by the bar and straddling the strip, said fingers having transverse openings therein, and a removable pin extending through the said openings and the strip when inserted between said fingers.
- 40 9. Means for installing an insert strip in a body of plastic material comprising a supporting member adapted to hold the strip in adjusted position while the plastic material is placed thereabout said supporting member having an opening therein, and a stake driven thru said opening in said support by which the support is directed in a plane of movement having fixed relation with the plane of the inserted strip upon the withdrawal of the supporting member from the body of material.
- 45 10. Means for installing an insert strip in a body of plastic material comprising a supporting member adapted to hold the strip in adjusted position while the plastic material is deposited thereabout, the supporting member being adapted to rest upon the edges of a mold for said body of plastic material, beyond the sides of which the supporting member extends, said supporting member having perforations therein beyond the sides of the mold, and stakes extending through said perforations and holding the supporting member against lateral displacement.
- 50 In testimony whereof, I have hereunto set my hand this 16th day of June, A. D. 1919.

HARRY C. FOSTER.
